UNITED STATES PATENT OFFICE.

ADELMER M. BATES, OF CHICAGO, ILLINOIS.

DESIGN FOR A BAG OR SACK.

SPECIFICATION forming part of Design No. 31,266, dated July 18, 1899.

Application filed September 26, 1898. Serial No. 691,943. Term of patent 14 years.

To all whom it may concern:

Be it known that I, ADELMER M. BATES, a citizen of the United States, residing at Chicago, in the county of Cook and State of Illinois, have invented and produced a new and original Design or Useful Shape for a Bag or Sack, of which the following, in connection with the accompanying drawings, is such a full, clear, and exact description thereof as to enable others skilled in the art to which my invention relates to make and use the same.

In the said drawings, Figure 1 is a side elevation of a bag or sack, showing the pattern of my design; and Fig. 2 is a plan or end view looking from the upper end as shown in Fig. 1.

The leading features of my design consist of a bag or sack having one end cut on the diagonal and transverse lines A B C, so that when viewed in side elevation, as in Fig. 1,

the bag will present the appearance of being 20 longer on one side than on the other.

The main or body portion D of the bag is substantially rectangular, and the transverse lines B C, which form the square corners at one end, are arranged at an obtuse angle to 25 the diagonal line A. The end of the bag along the line B is open, as shown in Fig. 2, and the rest of the bag at the irregular end is closed, E F being a rectangular line of stitching.

Having thus described my invention, what 30 I claim as new therein, and desire to secure by Letters Patent, is—

The design for a bag or sack substantially as herein shown and described.

A. M. BATES.
